UNITED STATES PATENT OFFICE.

CHARLES R. TAYLOR, OF FOSTORIA, MICHIGAN.

FIRE-ESCAPE.

1,249,855.

Specification of Letters Patent. Patented Dec. 11, 1917.

Application filed May 28, 1917. Serial No. 171,454.

To all whom it may concern:

Be it known that I, CHARLES R. TAYLOR, a citizen of the United States, residing at Fostoria, in the county of Tuscola, State of Michigan, have invented certain new and useful Improvements in Fire-Escapes; and I do hereby declare the following to be a full, clear, and exact description of the invention, such as will enable others skilled in the art to which it appertains to make and use the same.

This invention relates to improvements in fire-escapes and particularly to portable and foldable fire-escapes.

One object of the present invention is to provide a novel and efficient device of this character which can be quickly and easily applied to the window frame of a burning building and let down on the outside of the building to permit the person to escape.

Another object is to provide a device of this character which can be easily rolled into a small compass for disposition in a suit-case or hand bag.

Another object is to provide novel means for releasing the window engaging means after the person has descended to safety thereby permitting the recovery of the device.

Other objects and advantages will be apparent from the following description when taken in connection with the accompanying drawing.

In the accompanying drawing:

Figure 1 is a front elevation of my improved fire-escape applied to the window of a building.

Fig. 2 is an enlarged elevation of one of the window engaging hooks.

Fig. 3 is a vertical longitudinal sectional view through the said hook.

Fig. 4 is an enlarged elevation of a portion of the ladder.

Fig. 5 is a transverse sectional view taken on the line 5—5 of Fig. 4.

Fig. 6 is a sectional view similar to Fig. 3 but showing the hook in released position.

Referring particularly to the accompanying drawing 10 represents a pair of ropes

which form the side rails of the ladder. Secured to the ropes 10, at regularly spaced intervals, are the rungs 11. At approximately every fourth rung there is secured a transverse bar 12, on each end of which is hinged, at 13, a member 14, said member being adapted to be extended rearwardly of the ladder and to engage with the wall of the building to prevent the ladder from swinging thereagainst. These members are also arranged to be folded against the members 12 when the device is not in use. Carried by the center of each of the bars 12 is a ring 15, the purpose of which will appear hereinafter.

Carried by the upper ends of the ropes 10 are the vertically extending eye-bolts 16, and connected to these bolts are the sill engaging members 17. Each of the members 17 is provided with guide eyes 18 for the slideable reception of one portion of a hook member 19. Carried by the outer end of the hook member is an eye 20, and secured to this eye is one end of a cord 21, the said cord passing through a second eye 22 carried by the said member 19, and thence downwardly through all of the rings 15 of the bars 12, to the bottom of the ladder, where it can be grasped to pull the hook members slidably inward on the sill engaging members. This sliding movement of the hook members effectively releases the said members and the sill engaging members from the window frame, and permits the ladder to drop to the ground, thereby saving the ladder from destruction in the burning building.

It will thus be seen that I have provided a simple and efficient device whereby a person can quickly and easily escape from a burning building, and afterward recover the ladder for future use. Furthermore, the device can be readily rolled into a compact condition for packing in a suit-case, hand-bag or trunk, so that it can be transported from place to place and be at all times ready for use.

What is claimed is:

A fire-escape including a flexible ladder, sill engaging members movably connected to

the upper end of the ladder, slideable hook members carried by the sill engaging members for engagement with a window sill, guiding means carried by the ladder, and a
5 releasing means for the hook members disposed through the guiding means and operable from the ground.

In testimony whereof, I affix my signature in the presence of two witnesses.

CHARLES R. TAYLOR.

Witnesses:

A. J. EVELAND,
HARLEY MINER.
